& Atty.

UNITED STATES PATENT OFFICE.

EDWARD L. BESSE, OF FAIRHAVEN, MASSACHUSETTS.

WARPING-BEAM.

1,265,292.

Specification of Letters Patent. Patented May 7, 1918.

Application filed December 15, 1915. Serial No. 66,967.

To all whom it may concern:

Be it known that I, EDWARD L. BESSE, a citizen of the United States, residing at Fairhaven, in the county of Bristol and State of Massachusetts, have invented certain new and useful Improvements in Warping-Beams; and I do hereby declare the following to be a full, clear, and exact description of the invention, such as will enable others skilled in the art to which it appertains to make and use the same.

The invention relates to warping beams such as are commonly used in textile manufacture in transporting warp or yarn from one mill to another.

The primary object of the invention is to provide a novel and improved construction of warping beam in which the shaft which supports the barrel during the winding and unwinding of the warp or yarn may be readily removed or replaced. This enables the comparatively heavy shaft to be removed during transportation, with a resulting economy in weight and space, and also enables the same shaft to be used with different beam barrels with a resulting reduction in the number of shafts required. It is a further object of the invention to otherwise improve and simplify the construction of the warping beam whereby its strength and durability are increased. To these ends the invention comprises the features of construction and combinations of parts hereinafter described and set forth in the claims.

The several features of the invention are illustrated in the accompanying drawings, in which Figure 1 is a longitudinal vertical section of the improved warping beam, and Fig. 2 is a transverse section of the warping beam.

In the preferred form of the invention the barrel and heads of the beam are built up upon metallic bearings in which the beam shaft is centered and removably secured. A bearing 10 is located at each end of the beam, and has a cylindrical body portion 12 upon which the beam heads 14 are mounted and secured. A circumferential flange 16 projects out from the body portion of the bearing and serves to support and center the end of the barrel 18. Each bearing has a central conical bore 20 in which the shaft 22 may be removably mounted and centered. The bore 20, flange 16, and body portion 12 are finished concentric with one another so that the barrel built up on the bearings

will be concentric with the shaft when it is secured within the bearings.

The barrel 18 consists of lagging 24 which is secured around the periphery of a series of circular supporting disks 26. The lagging 24 and disks 26 are usually constructed of wood and are secured together by the ordinary fastenings, such as nails, or screws. In the preferred form of the invention the two end disks 26 are arranged to abut against the faces of the flanges 16, and another disk 26 is located approximately midway between the end disks, the number of supporting disks employed depending upon the length of the beam.

The heads 14 are usually built up of several layers of wood and have central bores 28 which fit over the body portions 12 of the bearings 10. A peripheral groove 30 is formed in each of the heads for the usual friction bands. To protect and reinforce its inner face and edge, each head is provided on its inner side with a thin metal disk 32, the edge of which is spun or otherwise bent to form a narrow flange embracing the periphery of the head inside of the groove 30. The outer surface and edge of each head may be and preferably is reinforced and protected by a similar disk applied to the outer side of the head and having a flange embracing the head outside the groove 30.

The heads, barrel and bearings, are held firmly together by means of a series of bolts 34 which run from one head entirely through the other head. These bolts serve to clamp the heads upon the bearings 10 and against the ends of the barrel 18. This gives a compact, strong structure which does not depend upon the shaft for holding the parts together or in central alinement. The bearing maintains the centering and rigidity of the parts and the flange 16 projects out under and flush with the end of the barrel to support and reinforce the ends of the lagging.

The shaft 22 has a fixed cone 38 near one end and nut 40 near the other end. A loose cone 42 is employed adjacent the nut 40 so that the shaft may be placed through the bearings and barrel and be self-centered by the cones 38 and 42.

With this construction it is only necessary to have a beam shaft for each machine in which the warping beams are to be used, since the shaft can be removed for the transportation of the beam and another shaft inserted when the yarn or warp is to be taken

from the beam. The removal of the shaft also materially reduces the weight to be transported, as well as the space required for their transportation.

- 5 In the specification and claims, portions of the beam have been described as constructed of "wood," but this term is not to be construed as a term of limitation, but merely as a term of description, since obviously any of 10 the well known substitutes for wood could be used. Wood has been employed in the construction of the beam because it is light and convenient.

Having thus described my invention, what 15 is claimed as new is:—

1. A warping beam comprising a barrel 20 consisting of wooden lagging attached to disks spaced from the ends of the lagging; metallic bearings mounted in the ends of the barrel outside the disks, said bearings having flanges to support the ends of the barrel, and body portions; heads mounted on the body portions with their inner faces against the bearing flanges and the ends of 25 the barrel; and means to clamp the barrel heads and bearings together.

2. A warping beam comprising a barrel,

wooden heads mounted at the ends of the barrel, band grooves formed near the center of the peripheral faces of the heads, and metallic reinforcing disks on the sides of the head, said disks having their edges bent over to embrace the edges of the heads and extending to the edges of the groove. 30

3. A warping beam comprising a hollow 35 barrel, bearings having flanges for supporting the ends of the barrel, wooden heads centered on the bearings, thin metal disks on opposite sides of the heads with their edges bent over to reinforce the edges of the heads, and bolts passing through the heads, disks and barrel to clamp the parts together. 40

4. A warping beam comprising a barrel 45 consisting of a wooden lagging attached to wooden disks, metallic bearings having flanges fitting within the ends of the barrel, and body portions extending beyond the ends of the barrel, heads mounted on the body portions of the bearings, and bolts extending from one head through the other to 50 clamp the heads against the ends of the barrel.

EDWARD L. BESSE.
